SAFETY GUARD FOR HINGED CHUTES

BACKGROUND AND SUMMARY OF THE INVENTION

In the handling of concrete from a fixed or mobile mixer, it is the practice to use a series of trough-shaped chutes which are hinged together either by permanent hinges or detachable hinges. The axes of the hinges are located adjacent the side rims of the chutes so that the bottom portions of the chute troughs move toward each other like opposing jaws as the chute sections are brought into alignment. The chute sections are relatively heavy so that should one have his hand or fingers between the chute sections, the engaged fingers or hand may be broken or in some cases actually severed.

The present invention is a safety device attached to one of an attached pair of chute sections which effectively prevents the placement of one hand or fingers in the danger area. Accordingly, the objects of this invention include:

First, to provide a safety guard for hinged chutes in the form of a fixed, essentially conical skirt projecting outwardly from one of the chute sections and clearing the mating chute a substantial distance so that one cannot insert his hand or fingers between the chutes.

Second, to provide a safety guard, as indicated in the preceding object, which serves as a handle in pivoting the more extended chute section about the mating chute, or fastening a removable outer chute section to its mating section.

Third, to provide a safety guard for chutes, which does not interfere with use of sectional chutes, but actually aids in the manipulation of the chutes.

DESCRIPTION OF THE FIGURES

FIG. 1 is a side view of a hinged chute incorporating the safety guard, the hinged chute being shown by solid lines in its extended position, by fragmentary broken lines in an intermediate position, and by dotted lines in a folded position.

FIG. 2 is a similar fragmentary side view, showing a removable further chute section in a partially folded relation with the extended section of the chute shown in FIG. 1.

FIG. 3 is an enlarged end view of one of the chute sections, taken from 3-3 of FIG. 2.

FIG. 4 is an enlarged partial elevational, partial sectional view, taken within circle 4 of FIG. 1, showing adjacent portions of the chute sections as they approach their relatively extended positions.

SPECIFICATION

Hinged chutes are used for the conveying of concrete from a mobile or fixed concrete mixer. Typically, such mixers are provided with a discharge funnel 1, indicated by broken lines in FIG. 1, to which is attached a mounting ring 2, preferably arranged so that it may be rotated. The receiving end of a first chute 3 is disposed under the mounting ring and is provided with flared flanges 4 which are connected to the mounting ring by pivot brackets 5 so that the angular position of the first chute may be adjusted. To avoid spillage of the concrete, the mounting ring is usually provided with a flexible skirt 6 which extends into the receiving end of the first chute.

The chute is trough-shaped, preferably semicylindrical, and may taper toward its discharge end. At the discharge end, the upper extremities of the side walls are provided with a pair of handle bars 7, to which is attached a second chute 8 having pivot brackets 9 at the extremities of its side walls. The first and second chutes have overlapping ends 10 and 11; that is, their adjacent ends overlap when the chutes are in their relatively extended positions. The pivot brackets 9 define an axis which is essentially diametrical with respect to the transverse section of the chute, and as shown, are joined to portions of the handle bar 7, which are also diametrically disposed. If desired, however, the pivotal elements which receive the brackets 9 may be separate from the handle bars.

Adjacent its overlapping end 10, the first chute is provided with a semicircular stop flange 12 and the overlapping end 11

5 of the second chute is provided with a semicircular reinforcing flange 13.

10 The extended end of the second chute may be equipped with handle bars 7. Preferably, in this case, the handle bars are provided with radially outward or laterally extending handle rods 14 which form pivot elements for a third chute 15. The third chute is provided with hook brackets 16, similar to the pivot brackets 9, except that the pivot ends are slotted to form with the rods 14 a separable hinge as distinguished from the fixed hinge formed by the handle bars 7 and the pivot brackets 9.

15 It is a conventional practice to fold the second chute 8 upon the first chute 3, as indicated by dotted lines in FIG. 1. This is particularly true if the chutes are mounted on a mobile mixer. If the distance from the mixer hopper 1 to the point of discharge of the concrete requires, then the third chute 15 or additional chutes are added.

20 The construction so far described is conventional. When it is desired to rotate the second chute about the first chute to place them in their extended operating condition, it can readily be seen that injury to one's hand or fingers is quite possible if the hand or fingers should be caught between the overlapping ends 10 and 11. The present invention is directed to a guard which eliminates this hazardous condition. The guard, designated 17, includes a semicircular radial portion 18, welded to the reinforcing flange 13, a semiconical portion 19 extending radially outward and axially therefrom so as to cover the overlapping end of the adjacent chute or chute section. The semiconical portion 19 terminates in a marginal bead 20. The guard extends peripherally to points close to the pivot brackets 9 or hook brackets 16 and the peripheral extremities are curved, as indicated by 21.

25 The dimensions of the guard 17 are such that it deflects one's hands or fingers away from the overlapping ends 10 and 11. Furthermore, the guard forms a handle which may be safely grasped to effect pivotal movement of a chute section into its extended position with respect to the adjacent chute.

30 While it is preferred to mount the guard 17 on the relatively extended chute, it should be noted that the guard may be mounted on the preceding chute.

35 While particular embodiments of this invention have been shown and described, it is not intended to limit the same to the details of the constructions set forth, but instead, the invention embraces such changes, modifications and equivalents of the various parts and their relationships as come within the purview of the appended claims.

7.

I claim:

- 50 1. A guard for a sectional chute having at least two semicylindrical sections joined by an essentially diametrically disposed pair of hinges, and movable between an extended position in which adjacent ends of the chute sections overlap and an angularly related position in which said adjacent ends are separated, said guard comprising:
55 a. a guard member fixed to one of said chute sections and including a guard rim disposed radially outwardly from the region of said overlapping adjacent ends.
- 60 2. A guard, as defined in claim 1, wherein:
a. said guard member is essentially semiconical having an end of smaller diameter joined to one chute section and an end of larger diameter forming said guard rim and axially overlapping the other chute section.
- 65 3. A sectional chute comprising:
a. at least a pair of trough-shaped chute sections having side walls and confronting ends dimensioned to overlap when the chute sections are in axial alignment;
b. mating hinge elements at the confronting ends of said chute sections joined to the extremities of said side walls for permitting relative pivotal movement of said chute sections whereby said confronting ends move to and from their overlapping relation; and
70 c. a guard member fixed to one of said chute sections and terminating in a guard rim disposed radially outwardly

- from said chutes to prevent access to said confronting ends when said ends are moved into overlapping relation.
4. A sectional chute, as defined in claim 3, wherein:
5. said guard member extends axially beyond the chute section to which it is fixed.
  5. A sectional chute, as defined in claim 3, wherein:
    5. one of said chute sections remains fixed while the other

- chute section rotates about the end thereof; and
5. said guard is secured to the rotatable chute section.
  6. A sectional chute, as defined in claim 3, wherein:
    5. said hinge elements form a separable hinge to permit removal of one of the chute sections; and
    5. said guard is secured to the removable chute section.
